TEXTILE ARTICLE AND THE MANUFACTURE
THEREOF

Elsa Hörler, Barcelona, Spain.

Application August 24, 1942, Serial No. 455,950
In Germany September 9, 1941.

4 Claims. (Cl. 28—78)

The present invention relates to a process for manufacturing knitted articles with closed loops and product obtained thereby.

In the manufacture of knitted garments and particularly of stockings, different methods have already been tried for the establishment of closed loops or meshes. The laddering of loops is a great drawback, especially in the case of silk and rayon stockings, for in these articles laddered loops form easily and frequently at the smallest breakage of thread, as a consequence of the lack of inter-adherence of the flat threads, while in case of knitted articles made with rough threads, such as wool etc., this laddering of loops does not occur so easily.

The formation of laddering loops in ordinary and plain knitted garments, such as stockings, is due to the structure of the loops, which, as is known, consists of loops disposed in horizontal rows, which are superposed in vertical rows, so that each loop is thus held exclusively by the loops of the neighbouring horizontal rows of loops, that is to say, above and below.

In the methods heretofore proposed for preventing the formation of laddering loops, modified interlacing of the loops has been suggested, that is to say, the loop structure has been modified, or special threads of warp or weft have been introduced. None of these suggestions, however, has found acceptance in the manufacture of stockings, owing to the fact that by the new structure of loops, the qualities of elasticity, softness, uniform aspect, fineness, transparency etc., appreciated and demanded by the market for this class of goods, have been entirely or partly lost.

The present invention refers to a process for manufacturing knitted articles with closed loops, in which the firmness of the loops is obtained by interlacing each loop, not only to the loops of the neighbouring horizontal rows of loops, but also to the two neighbouring loops of the same horizontal row of loops. The interlacement to the neighbouring loops of the same row of loops, is obtained by slinging the thread through the preceding lateral loop just before the formation of each new loop.

The horizontal rows of loops formed in this way have the particularity that they maintain their form independently, that is to say, out of the knitted texture, contrary to the horizontal rows of loops of an ordinary knitted texture, which only maintain their form in the texture together with other rows of loops, owing to the fact that they lack any lateral interlacement.

This particularity gives to the texture manufactured in accordance with the present invention the desired resistance against the laddering of loops, while it does not in any way differ from an ordinary plain knitted texture with regard to elasticity, softness, uniform aspect, fineness, transparency etc.

Some aspects of the invention are illustrated in the accompanying drawing, in which

10 Figure 1 shows diagrammatically and on a greatly increased scale, a horizontal row of loops, these loops being interlaced among themselves in accordance with the invention.

15 Figure 2 represents, diagrammatically and also on a greatly increased scale, a sectional view of a knitted texture composed of rows of loops as illustrated in Figure 1.

20 As can be seen in Figure 1, the thread 1 is passed through the preceding lateral loop just before a new loop is formed, so that each individual loop is connected with the neighbouring loops of the same row at the places indicated by 2. Such rows of loops, which maintain their form out of the texture, as stated above, that is 25 to say do not become undone, are then made up into a texture, as illustrated by Figure 2. This is achieved by forming first a horizontal row of loops A and afterwards interlacing in the inferior loops of this row A the loops of a second horizontal row B during its formation. A third row 30 C is then formed in the same way and interlaced to the inferior loops of the preceding row B, and so on.

35 The interlacing of the various loops in the corresponding loops of the preceding row of loops, may be accomplished as shown in Figure 2, that is to say each new loop is interlaced simultaneously to two inferior loops situated side by side of the preceding row, so that links are formed in the places indicated by 3 between two successive rows. However, each loop can also be merely interlaced to a single inferior loop of the preceding row, or any other scheme of interlacement of the rows among themselves can be followed, 40 for instance, by skipping one or more loops, as is also possible in ordinary plain knitting. The essential feature is that each single loop be not only interlaced to the preceding row of loops in any manner, but also simultaneously to the preceding lateral loop of the same horizontal row.

45 The formation of the texture of rows of interlaced loops in accordance with the invention, may be obtained by plain or circular knitting, but always horizontally. As the interlacement of the various rows of loops among themselves may be

carried out in any way, this process also provides for any desired enlargement or shortening of the texture. In plain knitting it is advantageous to link the various loops alternatively in one row from right to left and in the next row from left to right, firm selvages being always formed in this way. In round knitting the interlacing of the horizontal rows of loops is effected in spiral form, so that in this way also seamless stockings or other tubular goods can be manufactured.

I claim:

1. A method of making textile articles with a plurality of rows of closed loops consisting of alternate inferior and superior loops, which comprises interlacing the thread with a preceedingly formed superior loop just before a new superior loop is formed and with an inferior loop just before a new inferior loop is formed.

2. A textile article comprising a plurality of interlaced rows of closed loops, each row consisting of alternate inferior and superior loops with each inferior loop interlaced with each adjacent inferior loop and each superior loop interlaced with each adjacent superior loop.

3. A textile article comprising a plurality of interlaced rows of closed loops, each row consisting of alternate inferior and superior loops with each inferior loop interlaced with each adjacent inferior loop and each superior loop interlaced with each adjacent superior loop, each inferior loop of at least one row being also interlaced with at least one superior loop of an adjacent row and each superior loop of at least one row being also interlaced with at least one inferior loop of an adjacent row.

4. A textile article comprising a plurality of interlaced rows of closed loops, each row consisting of alternate inferior and superior loops with each inferior loop interlaced with each adjacent inferior loop and each superior loop interlaced with each adjacent superior loop, each inferior loop of at least one row being also interlaced with a plurality of superior loops of an adjacent row and each superior loop of at least one row being also interlaced with a plurality of inferior loops of an adjacent row.
